BOOTJACK

Rudolph M. De Andre, 3708 Garfield Ave. S.,
Minneapolis, Minn.

Filed Aug. 2, 1965, Ser. No. 86,400

Term of patent 14 years

(Cl. D7—2)

Fig 1

Fig 2

Fig 3

Fig 4

FIG. 1 is a top plan view of a bootjack showing my new design;

FIG. 2 is a side elevational view thereof;

FIG. 3 is a front elevational view thereof;

FIG. 4 is a rear elevational view thereof; and

FIG. 5 is a bottom plan view thereof.

The side opposite that shown in FIG. 2 is a mirror image of the side shown.

I claim:

The ornamental design for a bootjack, as shown and described.
